UNITED STATES PATENT OFFICE

FINN T. IRGENS, OF MILWAUKEE, WISCONSIN, ASSIGNOR TO OUTBOARD MOTORS CORPORATION, OF MILWAUKEE, WISCONSIN, A CORPORATION OF MICHIGAN

MOTOR SUPPORT

Application filed November 4, 1929. Serial No. 404,570.

This invention relates to improvements in motor supports.

It is the object of the invention to provide a novel and improved means for carrying an outboard motor in a recumbent position (when not in use) without injury to its fuel tank.

When outboard motors are laid down for any purpose, as for transportation, or as an 10 incident to manipulation in positioning or removing the motors from the boat, the motors are ordinarily laid upon the ground with the tiller handle uppermost. The design of outboard motors has heretofore been 15 such that in the position aforesaid, the fuel tank of the motor has contacted with the ground and has been subject to dents, scratches, and cuts which mar its appearance and tend to loosen the tank from its sup- 20 port and to cause it to leak.

To overcome these objections I have provided extended cooling fins on the muffler heads which perform the function of feet and project from the muffler beyond a plane 25 including the surface of the fuel tank and the point of support at the lower unit of the motor.

In the drawings:

Figure 1 is a side elevation of a motor 30 supported in accordance with this invention.

Figure 2 is a detail in perspective of the muffler shown in Figure 1 and exemplifying one way in which suitable supporting feet may be economically and inconspicuously formed on the motor.

Like parts are identified by the same reference characters in both views.

The outboard motor comprises a supporting bracket 5, bearing sleeve 6, tubular support 7, engine 8 and lower unit 9. The engine is provided with the usual fuel tank 10 and fly wheel magneto 11. The engine crank shaft is not illustrated but it will be understood to be extended through the tubular support 7 in the usual way and connected to drive the propeller 12.

When the motor is in a recumbent position, as illustrated in Figure 1, its lower unit is usually supported by the propeller 30 12 or the propeller nut 13. In accordance

with this invention the engine is provided with a means of support other than fuel tank 10 for keeping the upper end of the motor sufficiently remote from the ground so that the fuel tank will not contact there- 55 with.

For this purpose, I provide the usual heads 14 and 15 of the muffler 16 with feet 20 comprising extensions of the cooling fins for such heads. Although, obviously, the feet 20 might be otherwise provided, it will be noted that the particular arrangement disclosed is economical, serviceable and inconspicuous.

Inasmuch as the muffler heads comprise manifolds directly connected with the cylinder castings of the engine in accordance with usual practice, it will be obvious that the muffler itself, which is usually made of sheet metal, is relieved of load in addition to the relief afforded to the fuel tank. The muffler, however, is entirely adequate to brace the heads against displacement under any load to which they are subjected in performance of their new function of supporting the motor.

I claim:

1. In an outboard motor, the combination with an engine having a fuel tank so positioned as to lie therebeneath in the recumbent position of the motor, of a muffler for said engine provided with vents in its intermediate portions and supports for said engine adjacent the ends of the muffler and projecting beyond said tank and intermediate portions of the muffler, whereby to be adapted in the recumbent position of the motor to hold said tank and vented muffler portions off the ground.

2. In an outboard motor, the combination with an engine and a lower unit connected therewith and provided with means adapted to rest on the ground in the recumbent position of the motor, of a fuel tank for said engine positioned to lie therebeneath in said motor position, a muffler likewise located to lie beneath said engine in the recumbent position of the motor, and members at the ends of the muffler connected with said engine and provided with supports extending

beyond the muffler and fuel tank, whereby to carry the weight of the engine and to relieve the tank and muffler thereof.

3. In an outboard motor, the combination with an engine and a lower unit connected therewith and provided with means adapted to rest on the ground in the recumbent position of the motor, of a fuel tank for said engine positioned to lie therebeneath in said motor position, a muffler likewise located to lie beneath said engine in the recumbent position of the motor, and members at the ends of the muffler connected with said engine and provided with supports extending beyond the muffler and fuel tank, whereby to carry the weight of the engine and to relieve the tank and muffler thereof, said members comprising exhaust manifolds for said engine.
4. In an outboard motor, the combination with an engine and a lower unit connected therewith and provided with means adapted to rest on the ground in the recumbent position of the motor, of a fuel tank for said engine positioned to lie therebeneath in said motor position, a muffler likewise located to lie beneath said engine in the recumbent position of the motor and members at the ends of the muffler connected with said engine and provided with supports extending beyond the muffler and fuel tank, whereby to carry the weight of the engine and to relieve the tank and muffler thereof, said members comprising exhaust manifolds for said engine having cooling flanges extended to provide said supports.

5. In an outboard motor having cylinders at opposite sides of a central axis, the combination with said cylinders, of engine supports connected therewith substantially at the ends of said cylinders and projecting rearwardly at widely spaced points whereby to carry the weight of the cylinders directly and provide stable engine support in a recumbent motor position, and exhaust gas muffler means having less rearward extent than said supports, whereby to be protected by said supports in said motor position.

6. In an outboard motor having engine cylinders with these ends widely spaced laterally, the combination with said cylinders, of exhaust manifold castings connected with the cylinders near their ends and provided with rearwardly extending feet for the direct support of said cylinders in recumbent motor positions, and exhaust means less remote from said cylinders than said feet, whereby to be protected in recumbent motor positions.
